CLAIM

The ornamental design for a solar light, as shown and described.

DESCRIPTION

FIG. 1 is a front, left and top perspective view of a solar light showing my new design;

FIG. 2 is a rear, right and bottom perspective view thereof;

FIG. 3 is a front, left and top perspective view of the solar light of FIG. 1, shown in condition of use;

FIG. 4 is a front view of FIG. 1;

FIG. 5 is a rear view of FIG. 1;

FIG. 6 is a left side view of FIG. 1;

FIG. 7 is a right side view of FIG. 1;

FIG. 8 is a top plan view of FIG. 1; and,

FIG. 9 is a bottom plan view of FIG. 1.

The broken lines in the figures illustrate portions of the solar light that form no part of the claimed design.
